UTILITY GARMENT HANGER

Herman G. Alofs, Grand Rapids, Mich., assignor
to Alofs Manufacturing Company, Grand
Rapids, Mich., a corporation of Michigan

Application October 29, 1945, Serial No. 625,263

2 Claims. (Cl. 248—303)

1

This invention relates to a bracket construction and mounting therefore, which has been primarily designed for the hanging of garments though of course many other articles may be hung thereon and supported thereby. It is a primary object and purpose of the present invention to provide a construction of the type noted which is easily suspended, for example from the upper edge of the door or other equivalent support, is of a very simple construction, assembled in a very short time without requiring the use of tools, may be readily disassembled for carrying if wanted, in its assembled condition is secure against accidental or other than designed separation, and which in use under the weight of the articles supported is maintained locked against separation or disassembly.

An understanding of the invention may be had from the following description taken in connection with the accompanying drawing, in which

Fig. 1 is a perspective view of the bracket hanger construction of my invention.

Fig. 2 is a front elevation partly in vertical section, the section being taken on the line of 2—2 of Fig. 3.

Fig. 3 is a fragmentary side elevation of the inner end portion of the bracket or hanger, and

Fig. 4 is a vertical section and partial plan on the plane of line 4—4 of Fig. 2.

Like reference characters refer to like parts in the different figures of the drawing, and the sectional views are taken in directions indicated by the arrows.

In the construction embodying my invention, a plate of flat metal is formed having a vertical part 1, from which a horizontal flange 2 is bent rearwardly at right angles and terminates in a downturned lip 3. Said sheet metal supporting member may be hung over the upper edge of a door or other equivalent support.

The front vertical portion 1 is formed adjacent its upper end and a little to one side of the vertical middle line thereof with an outwardly pressed eye 4 integral with the part 1 to provide a vertically located socket. At the lower end of the socket 4 and to the opposite side of the vertical middle line of the part 1, a second socket member 5 or eye is pressed outwardly, making a socket of a horizontal character as distinguished from the vertical socket portion 4 and a third socket 6 is pressed outwardly substantially at the vertical middle line of the part 1 as shown.

A wire bracket or hanger arm is provided having a horizontal lower section 7 from which, at its inner end, a vertical arm 8 is bent at right

2

angles. The arm 8 at its upper end portion is bent laterally at right angles terminating in a horizontal section 9. At the outer end of the lowermost section 7 it is bent upwardly and back upon itself in a U-turn, providing a hook portion 10, from which an upwardly and inwardly inclined section 11 extends which, at its inner end portion, is bent downwardly to provide a terminal vertical section 12.

In the assembly, the free end of the section 9 is inserted through the vertical socket 6 from below and the bracket or hanger arm turned for the passage of the vertical arm 8 upwardly through the socket 6, the terminal section 9 being passed through the horizontal socket at 5. The vertical end section 12 at the inner end of the part 11 is then inserted downwardly through the vertical socket 4. The material of the rod 11 is of resilient metal and may be strained away from positions normally occupied to effect such assembly so that the parts, upon springing back to their regular and normal positions, will be located as shown in Fig. 1, with the lower end portion of the section 12 located at one side of the upper part of the vertical arm 8, interposing a stop against a movement which would disengage the section 9 from the socket 5 through which it is passed.

Upon the suspending of garment hangers with garments thereon, or other weights, on the arm described the parts are maintained in their normal position as shown in Fig. 1 and any accidental or undesired disconnection of the supporting plate member and the carrying arm is insured against.

For disassembly it is merely necessary to grasp the upper section 11 and spring the inner end portion thereof upwardly to disconnect section 12 from its retaining socket at 4, thereupon the vertical arm 8 may be moved laterally to disconnect the section 9 from its retaining socket 5 and then the bracket arm removed by moving the arm 8 and the section 9 downwardly through the vertical socket 6. This provides a ready and almost instant disassembly of the two members of the structure for easy carrying.

The construction described is simple, practical and very effective for the purposes for which it is designed. It is of course evident that the 50 socket loops, particularly those indicated at 5 and 6, are made sufficiently large that the assembly and disassembly as described may be readily performed. Preferably, in matching the vertical terminal section 12 with the vertical socket 5 through which it is passed, the bracket arm will

be strained toward the rear to bring the lower end of such terminal section 12 in alignment with the socket which receives it, this providing additional insurance against a disconnection of the part 12 from its receiving socket.

The invention is defined in the appended claims and is to be considered comprehensive of all forms of structure coming within their scope.

I claim:

1. In a construction as described, a vertical support plate having upper and lower vertical socket eye members therein, and a third horizontally located socket eye member at the lower end and to one side of the upper socket member, and an arm having a vertical section extending upwardly through the lower vertical socket member and at its upper end a laterally turned terminal section passing through said horizontal socket eye member, said arm at the lower end of said vertical section being extended outwardly and return bent 20 and extending to the supporting plate and having a vertical terminal section passing downwardly through the upper vertical socket eye member, said last mentioned terminal section overlapping, at its lower portion, the upper end of said first 25 mentioned vertical section of said arm to thereby

maintain the horizontal terminal section at the upper end of said vertical section against outward movement in its horizontal socket.

2. A construction as defined in claim 1, said socket eye members being pressed from the vertical supporting plate outwardly in the form of integral bands, the vertical socket eye members being slit at their upper and lower edges and the horizontal socket member slit at its vertical sides from the metal and pressed outwardly therefrom.
